GLOVE

Joseph Burkholz, Brooklyn, N.Y.

Application November 17, 1944, Serial No. 563,833

6 Claims. (Cl. 2-169)

1

This invention relates to improvements in gloves.

Broadly, it is an object of my invention to provide a better glove which can be manufactured more economically than heretofore.

More particularly, it is an object of my invention to eliminate certain seams to increase the wear, to provide a better fitting glove and to permit the hand to enter the glove more freely.

Still another object is to produce a glove from two (2) pieces of material to save handling and labor.

Another object is to bring the seams at the extremities of the fingers further forward to fit over the shape of the finger nails instead of at the tips in order to give better and longer wear at the fingertips.

Another object is to eliminate the seam at the crotch or wear point between the thumb and the palm of the hand to prolong the life of the glove.

I have, therefore, cut the thumb from the same material as the glove.

A further object is to obtain a better fitting glove, particularly at the wrist portion.

For a fuller understanding of the nature and objects of my invention, reference is had to the following detailed description in which:

Fig. 1 is a perspective view of my glove showing the inside and palm portion thereof.

Fig. 2 is a perspective view showing the outside portion.

Fig. 3 is a perspective view of the thumb portion only taken at line 3 of Fig. 1.

Fig. 4 is a plan view of a pattern used for making my glove.

Fig. 5 is a plan view of the pattern for the middle and ring finger.

Referring to the drawings, numeral 10 shown in Fig. 4 represents the main pattern for cutting the material for making the glove shown in the Figs. 1 and 2.

The pattern 10 has a thumb portion 11, index finger portion 12, middle finger portion 13, ring finger portion 14, a little finger portion comprising an outer portion 15 and an inner portion 16, an inner portion 17 for the index finger and an inner portion 18 for the thumb. By folding pattern 10 approximately along dot and dash line 19, the glove may be made by stitching edge 20 from point 21 to 22, to edge 23 from point 24 to point 25, forming seam 36 (Fig. 1) approximately to the crotch between the thumb and index finger. It is to be understood that in all instances, the material is joined by folding the edges inward and stitching along a line adja-

cent the actual edges. However, the glove may be stitched in various ways well known in the art.

The thumb is formed by stitching the thumb portion 11 along edge 26 from point 22 to point 27, to edge 28 from point 25 to approximately point 29, the inner thumb portion 18 being turned upward with the upper extremity 30 of outer thumb portion 11 stitched to the upper extremity 31 of inner thumb portion 18, so that the seam falls over the edge of the finger nail as can be seen in Fig. 1 at 35, the inside of the material being face to face.

The index finger and part of the glove between the thumb and index finger is formed by stitching the finger portion 12 along edge 32 from point 27 to 33 to the inner portion 17 along edge 29 from point 29 to point 34; the lowermost or crotch portion 37 being formed by stitching finger portion 12 from approximately point 38 to 33, to edge 40 (Fig. 5) from point 39 to point 41 of portion 42 for the middle finger 13.

The middle finger is formed by stitching the finger portion 13 adjacent edges 43 and 44 from point 33 to point 45, to insert piece 42 adjacent edges 46 and 47, respectively (see Fig. 5) forming seams 48 and 49 respectively (see Fig. 2). Portion 42 forms the inside and side portions of the middle finger. The lower edge 50 between points 65 and 66 of portion 42 is stitched to the portion adjacent edge 51 between points 52 and 53 (see Fig. 4), forming line 11 (Fig. 1).

The ring finger is formed by stitching the finger portion 14 adjacent edges 54 and 55 from point 45 to point 56, to the portion 57 adjacent edges 58 and 59, respectively (Fig. 5), forming seams 60 and 61, respectively (Fig. 2). Portion 57 forms the inside and side portions of the ring finger. The lower edge 62 between points 67 and 68 of portion 57 is stitched adjacent edge 63 between points 53 and 64 (Fig. 4), forming line 72 (Fig. 1).

The little finger is formed by stitching the outer portion 15 to the inner portion 16 adjacent edges 73 and 74, respectively. The crotch portion 75 between the ring and middle finger is formed by stitching edge 76 (Fig. 5) to edge 77 (Fig. 4) and edge 78 to the lower portion of edge 73.

At the ends of each of the fingers, the top seam falls over the edge of the finger nail when the glove is worn upon the hand. This will permit the glove to last longer and will prevent the finger nail from breaking or cutting the seams at the ends of the fingers. Furthermore, the bulk 55 created by the seams when such seams are at the

extreme ends, make a bulk which causes greater wear.

Another weak point of gloves now being worn is at the thumb crotch which has a seam at the crotch. Constant movement of the thumb weakens the thread and creates a constant strain upon the seam causing it to break in time. My glove eliminates the seam at this point as will be clearly seen in Figs. 1 and 3, the thumb being of one piece of material with the body of the glove.

It should also be noted that the curved edges 20 and 23 and the thumb are cut so that when the glove is formed it takes the same shape of both sides of the wrist which permits a snug fit at the wrist and allows the hand to enter and be removed freely and also enhances the appearance of the glove. The use of elastic at the wrist is therefore eliminated.

It should also be noted that all seams at the side and inside finger portions are eliminated which greatly increases the wearing qualities of the glove.

My glove construction also reduces the number of operations heretofore necessary in the manufacture of gloves, such as, seaming the thumb, inserting and attaching the thumb to the glove, setting in the pieces between the fingers (fourchetting or kieling), sewing the entire glove together and trimming the glove. In making my glove all that is necessary is to set in the one piece consisting of the portions 42 and 51 and close the glove, thus saving a great deal of labor and resulting in a better appearing and more lasting glove.

It is understood that various changes and modifications may be made in the finish, combinations of materials, shaping and finishing below the wrist, and general designing and adaptation for different sizes without departing from the general spirit of the invention.

I claim:

1. In a glove of the character described, a main portion comprising portions for a complete thumb, index finger and little finger, back portions for a middle and ring finger, palm and wrist, and an insert portion for the inside and side portions of the middle and ring fingers.

2. In a glove of the character described comprised of two pieces stitched together, one of said pieces forming the entire glove except the inside and side portions of the middle and ring finger,

the other piece forming the inside and side portions of the middle and ring finger.

3. In a glove of the character described, a main portion comprising portions for a complete thumb, index finger, and little finger, back portions for a middle and ring finger, palm and wrist, and an insert portion for the inside and side portions of the middle and ring fingers, the opposite sides of said main portion forming said thumb without a seam at the crotch of said thumb.

4. In a glove of the character described, a main portion comprising portions for a complete thumb, index finger and little finger, back portions for a middle and ring finger, palm and wrist, and an insert portion for the inside and side portions of the middle and ring fingers, the opposite sides of said main portion forming said thumb without a seam at the crotch between said thumb and the index finger.

5. In a glove of the character described, comprised of two pieces stitched together, one of said pieces forming the entire glove except the inside and side portions of the middle and ring finger, the other piece forming the inside and side portions of the middle and ring finger, the stitching at the finger ends being under the finger nails when the fingers are inserted in the glove.

6. In a glove of the character described comprised of two pieces stitched together, one of said pieces forming the entire glove except the inside and side portions of the middle and ring finger, the other piece forming the inside and side portions of the middle and ring finger, no seams being present at the inside and side finger portions of said glove.
